Att'y.

UNITED STATES PATENT OFFICE.

GEORGE A. MCINTIRE, OF STAMFORD, CONNECTICUT.

FALSE-CUFF HOLDER.

SPECIFICATION forming part of Letters Patent No. 252,789, dated January 24, 1882.

Application filed May 7, 1881. (No model.)

To all whom it may concern:

Be it known that I, GEORGE ALEXANDER MCINTIRE, of Stamford, in the county of Fairfield and State of Connecticut, have invented 5 a new and useful False-Cuff Holder; and I do hereby declare that the following is a full and exact description thereof, reference being had to the accompanying drawings, making part of this application.

10 My invention relates to a novel construction of that kind of cuff-holder which is adapted to effect a securing of the cuff to the inner portion of the coat-sleeve in such manner that, without changing the relative position of the 15 holder device to the sleeve, the cuff may be adjusted to and may be held in any desired relative position to the lower end of the coat-sleeve; and it consists essentially in a cuff-holding contrivance composed of a main or 20 body portion adapted to be secured at one end to the lining or interior of the coat-sleeve and a transversely-arranged clamping or gripping device adapted to grasp the outer overlapping edge of the false shirt-cuff and hold the latter 25 in place, permitting, however, any desired adjustment of the cuff which the wearer may desire to effect, all as will be hereinafter more fully explained.

To enable those skilled in the art to which 30 my invention appertains to understand and practice the same, I will now proceed to more fully explain the same, referring by letters to the accompanying drawings, in which I have illustrated my invention in a form in which I have successfully practiced it and shown the 35 best mode of carrying out the same now known to me.

In the accompanying drawings, which form a part of this specification, Figure 1 is a perspective view of a shirt-cuff and the lower part 40 of a coat (and shirt) sleeve, with the cuff adjustably attached to the coat-sleeve by means of a device or contrivance made according to my invention. Fig. 2 is an elevation or side 45 view of the cuff-attaching implement or device detached from the cuff and coat-sleeve, and drawn on a larger scale than at Fig. 1, to more clearly illustrate its construction. Fig. 3 is a side elevation taken from an opposite point 50 of view and on the same scale as the last.

named figure. Fig. 4 is an edge view of the same, showing in sectional broken lines (and on an exaggerated scale) a portion of the coat-sleeve and in heavy dotted lines part of the cuff, for the purpose of illustrating the mode of 55 securing of the device to the coat and the manner in which it clamps and holds in place the overlapped edge of the cuff. Fig. 5 is an end view of the device, looking at its lower end, and showing in broken sectional lines and in heavy 60 dotted lines, respectively, portions of the coat-sleeve and cuff. At Fig. 6 is shown in side view or elevation a modified form of the cuff-holding clasp or device, in which, in lieu of a construction adapted to permit the attachment 65 of the upper end of the device to the coat-sleeve by means of penetrating points and hooks, is shown a form of device adapted to have its upper end attached to the coat-sleeve by means of a button on the device which en- 70 gages with a button-hole strip of suitably flexible material permanently fastened at the proper point to the interior or lining of the coat-sleeve. Fig. 7 is a cross-sectional view of this modified form of cuff-holder at the line $x x$ of Fig. 75 6; and Fig. 8 is an edge view of the same, showing also in section a part of the coat-sleeve and the button-hole strip fastened thereto. At Fig. 9 is shown an edge view of the same, 80 (together with part of the coat-sleeve in section,) in which the latter is attached to the coat-sleeve by means of a button permanently secured to the inner portion of said sleeve, with which button said contrivance may be engaged and disengaged at pleasure, and in which 85 (as in the contrivance shown at Figs. 6, 7, and 8) the cuff-edge is clasped or clamped between the main body portion and the spring tongue-like portions of the sheet-metal device. Fig. 10 is a partial side view of the device seen at 90 Fig. 9.

In the several figures of each form of contrivance shown the same part will be found designated by the same letter of reference.

In Figs. 1 to 5, inclusive, the cuff-holder is 95 made of two pieces of wire bent and secured together, as shown, so that one piece (see Fig. 2) forms the loop-like portion a , the shank portion b , and the two hooks $c c$, while the other piece of wire (see Fig. 3) forms the finger or 100

tongue-like device *d*, the pin *e*, and the shank *f*, the two pieces of wire being soldered or otherwise fastened together for a portion of the distance, during which their shank-like parts *b* and *f* are arranged in line and close together. In the said figures, *G* is the false cuff, *H* is portion of a coat-sleeve, and *I* part of a shirt-sleeve.

In the use of the cuff-holder of the form or construction shown in these figures that end of the implement or device shown at which are located the hooks *c c* and the pin or sharpened wire *e* is secured to the interior of the sleeve by inserting into the lining or other material of the coat-sleeve the said pin-point *e* and hooks *c c* in the condition or position clearly illustrated at Figs. 1 and 4; and this securing of this portion of the device or contrivance to the material of the coat-sleeve is effected by first forcing in the hooks *c c* until inserted clear up to their roots, and then slightly pressing into the material the sharp point of the pin-like device *e* by moving the device slightly in a direction operating to withdraw the hooks *c c* until the point of *e* shall have been just fairly and fully hooked or caught in. Having thus secured one end of the cuff-holder to the inside of the coat-sleeve *H*, the overlapping or outer edge, *g*, of the cuff *G* is slipped in between the loop-like portion *a* and the tongue-like part *d* of the other end of said holder, as clearly shown, and is clamped between the parts *a* and *d* with sufficient tenacity to insure the retention in place relatively to the coat cuff of the false shirt-cuff *G*. The tongue-like part *d* is slightly yielding, and being sprung out of its normal position and slightly away from the plane of the adjacent side of the loop *a* by the enforcement between said parts *a* and *d* of the stiffened edge *g* of the shirt-cuff, said tongue *d* operates to slightly corrugate or crimp the edge of the cuff between itself and the loop-like device *a*, and thus prevent any dropping down, or, in other words, any displacement endwise of the cuff *G* relatively to the holder device, and consequently relatively to the coat cuff or sleeve *H*.

If deemed expedient, the surface of the loop *a* may be roughened, as illustrated at Fig. 3, to insure a tighter gripe of the clamping devices on the cuff's edge.

From the foregoing explanations, in connection with the drawings, it will be seen that the cuff may have its edge *g* secured between the gripping parts of the cuff-holder at any desired point along the length of said edge, and that thus the lower end of the cuff *G* may be adjusted to any given relation to the end of the coat cuff or sleeve *H*, so that more or less or none of the shirt-cuff shall project below or beyond the lower edge of the coat-cuff; and it will be understood that after having been once secured in place, as shown, for instance, at

Fig. 1, the cuff *G* may be conveniently moved up or down within the coat-sleeve and set at 65 different relative positions with the end of the latter by simply either forcibly sliding the edge *g* along within the gripping devices of the cuff-holder or releasing said edge from said gripping devices and reinserting it between them 70 without removing or changing the relation to the coat sleeve of the cuff-holder implement or contrivance.

In the modification of cuff-holder shown at Figs. 6, 7, and 8 the holder is composed of 75 sheet metal instead of wire, and consists of a main or body portion, *f*, out of which is cut and slightly sprung up a tongue-like device, *i*, the upper end of the holder being provided with a button, *s*, of metal or other material, 80 which is adapted to be buttoned into the hole of a strip or loop, *g*, of any suitably flexible material, stitched or otherwise permanently secured at each of its ends to the inner portion or lining of the coat-sleeve *H*, as most clearly 85 seen at Fig. 8. In this form of holder the free end of the tongue *i* is sprung away from the surrounding portion of the part *f* and the edge *g* of the shirt-cuff is clamped between said portions of the parts *i* and *g* in a manner which 90 must be perfectly apparent.

In the form of holder seen at Figs. 9 and 10 the cuff clamping or gripping portion of the device is the same as that of the holder seen at Figs. 6, 7, and 8; but in lieu of having a button adapted to engage with a button-hole strip, it has simply an oblong eye, as seen plainly at *m*, Fig. 10, with which engages the shank of a T-shaped button device or fastener, *o*, (see Fig. 9,) permanently attached to the lining or interior of the coat-sleeve *H*. 100

The cuff *G* may be also temporarily secured at some point by a button or stud to the shirt-sleeve, if desired, and if the shirt-sleeve be long enough, since in such case the shirt-sleeve will not prevent the adjustment of the false cuff *G* to and its retention in any desired relative position to the coat-sleeve. 105

What I claim as my invention, and desire to secure by Letters Patent, is— 110

As an improved contrivance for holding in place a false shirt-cuff or wristband, a cuff-holder composed of a main or body portion adapted to be either permanently or temporarily secured to the inner portion of the coat-sleeve, and a clamping device arranged transversely to said main portion of the contrivance and adapted to grasp with a yielding pressure the outer overlapping edge of the cuff, all substantially as set forth. 115

In witness whereof I have hereunto set my hand this 21st day of April, 1881.

G. A. MCINTIRE.

In presence of—

D. B. CAREY,

CHARLES E. HOLLY.
